Primary Examiner — Karen E Eldridge Powers

(57) **CLAIM**

The ornamental design for an electric toothbrush set, as shown and described.

DESCRIPTION

FIG. 1 is a perspective view of a support for an electric toothbrush set, shown separately for clarity of illustration and in an open configuration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the support for the electric toothbrush set where the support is in a closed configuration;

FIG. 10 is a perspective view of a decorative component of the electric toothbrush set, shown separately for clarity of illustration;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof;

FIG. 18 is a perspective view of the support and the decorative component, shown in use with the decorative component installed on the support;

FIG. 19 is a perspective view of the electric toothbrush body of the electric toothbrush set, shown separately for clarity of illustration;

FIG. 20 is another perspective view thereof;

FIG. 21 is a front elevational view thereof;

FIG. 22 is a rear elevational view thereof;

FIG. 23 is a left side elevational view thereof;

FIG. 24 is a right side elevational view thereof;

FIG. 25 is a top plan view thereof;

FIG. 26 is a bottom plan view thereof;

FIG. 27 is a perspective view of the electric toothbrush set, shown in use with the electric toothbrush body hung on the support where the support is in the closed configuration; and, FIG. 28 is a perspective view of the electric toothbrush set, shown in use with the electric toothbrush body hung on the support where the support is in the opened configuration.

The broken lines in the drawings depict portions of the electric toothbrush set that form no part of the claimed design.

1 Claim, 28 Drawing Sheets
